DESIGN FOR A CUPBOARD

Arthur W. Lovejoy, Lowell, Mass., assignor to Philip I. Morehouse, Methuen, Mass.

Application November 15, 1938, Serial No. 81,094

Term of patent 7 years

To all whom it may concern:

Be it known that I, Arthur W. Lovejoy, a citizen of the United States, residing at Lowell, in the county of Middlesex and Commonwealth of Massachusetts, have invented a new, original, and ornamental Design for a Cupboard, of which the following is a specification, reference being had to the accompanying drawing forming part thereof.

In the drawing:

Fig. 1 is a perspective view of a cupboard showing my new design;

Fig. 2 is a front elevation of the cupboard shown in Fig. 1; and

Fig. 3 is a plan view of the cupboard shown in Fig. 1.

I claim:

The ornamental design for a cupboard, as shown.

ARTHUR W. LOVEJOY.
